UNITED STATES PATENT OFFICE.

STEPHEN E. ELLIOTT, OF WEST SALEM, ILLINOIS.

TRAP-NEST.

1,127,210.

Specification of Letters Patent.

Patented Feb. 2, 1915.

Application filed April 1, 1914. Serial No. 828,691.

To all whom it may concern:

Be it known that I, STEPHEN E. ELLIOTT, a citizen of the United States, and a resident of West Salem, in the county of Edwards and State of Illinois, have made certain new and useful Improvements in Trap-Nests, of which the following is a specification.

My invention is an improvement in trap nests, and has for its object to provide a nest of the character specified, so arranged that the entrance of a fowl to the nest will close one entrance and open another, so that a record may be kept of the various 10 fowls, the arrangement being such that when the fowl has left the nest the parts will return to their original position.

In the drawings: Figure 1 is a front view of the improved nest with the parts in one 20 position, Fig. 2 is a longitudinal vertical section, with the parts in another position, and Fig. 3 is a section on the line 3—3 of Fig. 2.

The present embodiment of the invention 25 comprises a casing consisting of front and rear walls 1 and 2, and end walls 3 and 3^a, the said casing being rectangular in cross section, and the bottom is preferably open, as indicated at 4. The casing is closed by 30 a cover plate 5 having a depending continuous flange 6, which fits outside of the upper end of the casing, and the cover may be removed for purposes of cleaning or the like.

35 The opening 4 of the bottom does not extend from one end of the casing to the other, but a web 7 is left at each end, extending from the adjacent end toward the opposite end, and lugs 8 are provided at the inner 40 end of each web and near the opposite side walls of the casing.

The front wall 1 is provided with openings 9 and 9^a, the former being the entrance, and the latter the exit, and a fan 45 shaped or substantially triangular plate 10 is provided for alternately closing the door openings. The plate is pivoted to the front wall of the casing by means of a pivot pin or rivet 11, and the door plate is arranged 50 with its large end downward, the said large end being rounded, as shown, and the apex of the plate extends above the pivot pin 11 upon which the plate swings.

A platform 12 is arranged within the casing at the bottom thereof, and the platform 55 is provided at each side with a depending

triangular flange 13, the said flanges being of greatest thickness at the center of the platform and gradually decreasing in thickness toward each end. The platform is 60 mounted to swing on a shaft 14, which is arranged transversely of the casing, and supported by the front and rear walls, and the flanges 13 are provided with openings at 65 their apices, through which the shaft 14 passes.

The platform is mounted to swing freely on the shaft 14, and the stops 8 are provided for permitting the downward movement of the ends of the platform the stops engaging 70 the said ends, as shown more particularly in Fig. 2, to limit the rocking movement of the platform. A box nest 15 is arranged at the end of the platform adjacent to the door opening 9^a, and a weight 16 is arranged on 75 the platform at the opposite end.

A door plate 17 is arranged in the casing at the door opening 9, the said plate having a transverse bearing 18 near its upper end and on one face, through which is 80 passed a shaft 19, the shaft being supported by the front and rear walls. The door plate 17 is cut away at the side edge adjacent to the door plate 10, as indicated at 20, to permit the plates 10 and 17 to swing 85 freely past each other, and a stop rod 21 is arranged transversely of the casing above the door plate, to limit the swinging movement of the plate. The rod or shaft 21 is adapted for engagement by the upper end 90 of the door, and consequently limits the swinging movement of the plate 17 to the position shown in Figs. 2 and 3.

A flexible member 22 is connected at one end to the top of the plate 17, as indicated 95 at 23, and the other end of the flexible member is connected to the adjacent end of the platform, as indicated at 24. A standard 25 extends upwardly from the center of the platform, at the side adjacent to the door 100 plate 10, and the upper end of the standard plate 10, and the upper end of the standard 105 is tubular, as shown at 26. A coil spring 27 is connected at one end to the platform directly above the shaft 14, and the other end of the spring is connected to the apex of the plate 10, as indicated at 28.

The operation of the improved trap nest is as follows: The weight 16 is sufficient to normally hold the parts in the position of Fig. 1. When in this position the door 110 plate 17 is almost horizontal, and near the top of the casing. The door opening 9 is

open, the door plate 10 being over the exit 9^a, and the view of the nest 15 from the door opening 9 is unobstructed. The coil spring 27 will hold the door plate in the position indicated in dotted lines in Fig. 1, or in the position indicated in full lines in Fig. 2. When the platform rocks, the upper end of the door plate 10 is swung in the same direction as the platform rocks. The connection 10 between the standard 25 and the apex of the door plate is a yielding connection, and the tubular portion 26 of the standard will cause the upper end of the door plate 10 to swing when the platform rocks. The hen looking 15 for a nest will look into the door opening 9, and will see the nest at the opposite end, the nest being in a retired position, which will attract the hen. The hen enters stepping upon the platform and walks toward 20 the nest. Her weight will overbalance the platform and will cause it to swing as indicated in Fig. 2. The door plate 10 now swings away from the opening 9^a into a position over the opening 9, and the plate 25 17 swings down into the position shown in full lines in Fig. 2 so that the hen cannot return toward the opposite end of the nest. After an egg has been laid the hen will pass 30 out by the opening 9^a. As soon as her weight passes off of the platform, the weight 16 will swing the platform, and will return the parts to the position of Fig. 1.

In practice, the improved nest is so arranged that the door opening 9 is in one 35 yard or compartment and the door opening 9^a in the other. A partition 30 may be arranged between the door openings, if desired, as shown in dotted lines in Fig. 3. Thus the non-producing fowls can be weeded 40 from the producing fowls. At the end of the day, the hens that have been through the nest will be in the compartment or pen into which the door opening 9^a opens, and the non-producers will be in the pen adjacent to 45 the door opening 9.

The device is easily cleaned since the entire interior is accessible when the top is removed. The open bottom also assists in cleanliness. The nest may be moved from 50 place to place as may be desired, and since all of the parts are metal, the nest may be scalded or otherwise purified. The support 25 and the coil spring 27 will swing the door plate 10 whenever the platform is rocked, and the spring acts as a lock or securing device for holding the parts against accidental displacement.

I claim:—

1. A device of the character specified, 60 comprising a casing having in one side wall a plurality of door openings, the said openings being on opposite sides of the center of the said side, a door plate pivoted to the front wall of the casing between the door openings and mounted to swing from side to

side to alternately close the door openings, a platform extending longitudinally of the casing and pivoted to the casing at the center of the platform, a box nest at one end of the platform, a weight at the opposite end and arranged to overbalance the nest, a support extending upwardly from the center of the platform at the side adjacent to the door plate and having a tubular bearing at its upper end, a coil spring connected at one end to the platform and extending through the bearing at the opposite end, and connected to the door plate above its pivotal connection for swinging said plate when the platform is swung, a door plate arranged transversely of the casing adjacent to the end of the platform provided with the weight, a pivotal connection between the plate and the casing near the upper end of the plate, a connection between the upper end of the plate and the adjacent end of the platform for swinging the said plate into approximately horizontal position when the weighted end of the platform is depressed, and for permitting the said plate to swing transversely of the casing between the door openings when the nest end of the platform is depressed, a stop for limiting the swinging movement of the last-named plate to a position transverse to the casing, and stops at each end of the casing for limiting the downward movement of the adjacent ends of the platform.

2. A device of the character specified, comprising a casing having in one side wall a plurality of door openings, the said openings being on opposite sides of the center of the said side, a door plate pivoted to the front wall of the casing between the door openings and mounted to swing from side to side to alternately close the door openings, a platform extending longitudinally of the casing and pivoted to the casing at the center of the platform, a box nest at one end of the platform, a weight at the opposite end and arranged to overbalance the nest, a support extending upwardly from the center of the platform at the side adjacent to the door plate and having a tubular bearing at its upper end, a coil spring connected at one end to the platform and extending through the bearing at the opposite end, and connected to the door plate above its pivotal connection for swinging said plate when the platform is swung, a door plate arranged transversely of the casing adjacent to the end of the platform provided with the weight, a pivotal connection between the plate and the casing near the upper end of the plate, a connection between the upper end of the plate and the adjacent end of the platform for swinging the said plate into approximately horizontal position when the weighted end of the platform is depressed, and for permitting the said plate to swing transversely of the casing

- between the door openings when the nest end of the platform is depressed. 35
3. A device of the character specified, comprising a casing having in one side wall a plurality of door openings, the said openings being on opposite sides of the center of the said side, a door plate pivoted to the front wall of the casing between the door openings and mounted to swing from side to side to alternately close the door openings, a platform extending longitudinally of the casing and pivoted to the casing at the center of the platform, a box nest at one end of the platform, a weight at the opposite end and arranged to overbalance the nest, a support extending upwardly from the center of the platform at the side adjacent to the door plate and having a tubular bearing at its upper end, a coil spring connected at one end to the platform and extending through the bearing at the opposite end, and connected to the door plate above its pivotal connection for swinging said plate when the platform is swung. 40
- 10 alternately close the door openings, a platform extending longitudinally of the casing and pivoted to the casing at the center of the platform, a box nest at one end of the platform, a weight at the opposite end and arranged to overbalance the nest, a support extending upwardly from the center of the platform at the side adjacent to the door plate and having a tubular bearing at its upper end, a coil spring connected at one end to the platform and extending through the bearing at the opposite end, and connected to the door plate above its pivotal connection for swinging said plate when the platform is swung. 45
- 15 to the platform and extending through the bearing at the opposite end, and connected to the door plate above its pivotal connection for swinging said plate when the platform is swung, means within the casing for closing the casing between the door openings, and a connection between the said means and the platform for moving the said means into operative position when the nest end of the platform is depressed. 50
- 20 4. A device of the character specified, comprising a casing having in one side wall a plurality of door openings, the said openings being on opposite sides of the center of the said side, a door plate pivoted to the front wall of the casing between the door openings and mounted to swing from side to side to alternately close the door openings, a platform extending longitudinally of the casing and pivoted to the casing at the center of the platform, a box nest at one end of the platform, a weight at the opposite end and arranged to overbalance the nest, a support extending upwardly from the center of the platform at the side adjacent to the door plate and having a tubular bearing at its upper end, a coil spring connected at one end to the platform and extending through the bearing at the opposite end, and connected to the door plate above its pivotal connection for swinging said plate when the platform is swung. 55
- 25 means at one end of the platform for normally overbalancing the said end, and a connection between the platform and the plate for swinging the said plate when the platform is rocked. 60
